COOLING SYSTEM FOR INTERNAL-
COMBUSTION ENGINES

Edward F. Chandler, Brooklyn, N. Y.

Application January 31, 1945, Serial No. 575,498

14 Claims. (Cl. 123—174)

1 This invention relates to cooling systems for internal combustion engines, and has for its principal object the provision of an improved system for controlling the temperature of the lubricating oil thereof, and also for controlling the temperature of the engine cooling water.

The use of heat exchangers in connection with marine installations of internal combustion engines has become practically universal. A common arrangement for Diesel engine cooling systems provides two heat exchangers; one for cooling the engine jacket water, and the other for cooling the engine lubricating oil. Sea water is circulated through these heat exchangers as the coolant, the usual arrangement providing for series flow of the sea water, first through the lubricating oil heat exchanger and thence through the jacket water cooler.

A somewhat less common engine cooling system provides for cooling the engine jacket water, as described above, but instead of circulating sea water through the lubricating oil cooler, the cooled jacket water is employed as the cooling medium. This type of cooling system has the advantage of exposing only one of the two heat exchangers or coolers to the corrosive action of sea water, and the further advantage that, upon starting a cold engine, the engine and the lubricating oil and the jacket water temperatures are elevated to the proper operating temperature range much more rapidly than when the colder sea water is circulated through the lubricating oil cooler. This type of cooling system has the disadvantage of requiring the use of somewhat larger heat exchangers for a given installation, which, to some extent, offsets the advantages derived therefrom.

However, the advantage obtained by circulating jacket water through the lubricating oil cooler, that is to say, the initial rapid heating of the engine lubricating oil and maintenance of optimum lubricating oil temperature during operation, has become extremely important in view of current operations of Diesel engine propelled naval vessels in the Northern and Southern cold sea areas. Reports show that, in many cases, the chilled engine lubricating oil in vessels operating in these areas, and not equipped for jacket water circulation through the lubricating oil coolers, never reaches the proper operating temperature even after hours of engine operation, resulting in accelerated wear of all bearing surfaces, early engine failure, decreased reliability, and excessive maintenance and repair requirements. This is particularly true in the case of

high-speed Diesel engines, and it has been definitely established that engine deterioration is very rapid whenever operation proceeds with either lubricating oil or jacket water circulating at a temperature below 130° F.

2 The principal object of the present invention is to avoid the difficulties encountered by the use of sea water circulating through the lubricating oil cooler, and to take maximum advantage of circulating jacket water through such cooler for rapid heating of the chilled lubricating oil upon for automatic control of the temperatures of the starting cold engines, and, in addition, to provide for automatic control of the temperatures of the lubricating oil and jacket water within the optimum operating range, as specified by the engine designer, regardless of variations in the power at which the engine is operated, or variations in the temperature of the sea water.

20 With these and other objects in view, as well as other advantages that may be incident to the use of the improvements, the invention consists in the parts and combination thereof hereinafter set forth and claimed, with the understanding that the several necessary elements constituting the same may be varied in proportion and arrangement without departing from the nature and scope of the invention, as defined in the appended claims.

30 In order to make the invention more clearly understood, there are shown in the accompanying drawings means for carrying the invention into practical use, without limiting the improvements in their useful application to the particular construction, which, for the purpose of explanation, has been made the subject of the illustrations.

Fig. 1 of the accompanying drawing is a diagrammatic view of a system of automatically controlling the temperature of the lubricating oil and jacket water of an internal combustion engine wherein the jacket water, by a simple and improved method, is employed to control the temperature of the lubricating oil; and

45 Fig. 2 is a modification of Fig. 1.

Like numerals in both figures of the drawing refer to similar parts.

Referring to the drawings, a system for controlling the temperature of the lubricating oil and jacket water of an internal combustion engine is shown as comprising, generally, an engine 1, a jacket water cooler 2, and a lubricating oil cooler 3. The jacket water cooler 2 is provided with a heat transfer element 4, through which sea water is circulated from pipe 5 and

valve 6, and from which the sea water escapes through pipe 1. This cooler is also shown as provided with a heat transfer element 8, through which jacket water to be cooled is supplied from the engine. The cooled jacket water escapes from the heat transfer element 8, through pipe 9, in which is positioned a thermal-responsive control element 16. The element 16 is preferably adjustable to function at a predetermined temperature change to increase or decrease the flow of jacket water by operating valve 11, which is operatively connected therewith by the means 12. The valve 11 is positioned in the by-pass pipe 13 between pipe 14, through which jacket water is delivered to the element 8, and the jacket water return pipe 9.

Heated jacket water from the engine 1 is delivered by pipe 15 through the three-way, automatically-controlled valve 16 to the inlet side of the heat exchange element 17, situated in the cooler 3, the escape end of said element being connected with pipe 14. A by-pass pipe 18, connected at one end with the valve 16, connects with pipe 14. Lubricating oil is circulated from the engine 1 through pipe 20, through the heat exchange element 21, and back to the engine through pipe 22. In the by-pass pipe 23, a pressure-relief valve 24 may be provided. Situated in pipe 22 is an adjustable, thermal-responsive element 25, which, through suitable means 26, is adapted to control the valve 16 in response to changes in the temperature of the lubricating oil in pipe 22, so as to increase or decrease the flow of water in the by-pass pipe 18. For simplicity, temperature and pressure-indicating means, and other auxiliary equipment common to systems of this order, have not been shown in the drawing.

Valve 6, which may be manually or automatically operated, serves to control the quantity of sea water passing through the element 4 in cooler 2. If desired, the same purpose may be served by the provision of a circulating water by-pass around this cooler. Lubricating oil from the engine may also be by-passed around the lubricating oil heat exchanger and directly back to the engine through the by-pass pipe 23, and an automatic, spring-loaded, pressure-relief valve 24, when the engine is initially started. The by-pass pipe 23 can be arranged to by-pass other parts of the engine lubrication system as well as the heat exchanger 3, such as lubricating oil filters, strainers, etc.

In operation of this improved system, upon initially starting the engine, and with the engine in operation, the jacket water is rapidly heated, and this heated water directly enters the heat exchanger 3, providing for rapid heating of the chilled lubricating oil circulating through the oil heat exchanger.

In this connection, it will be understood that in most types of internal combustion engines, the amount of heat dissipated into the jacket water by the operation of the engine is about ten times the amount of heat dissipated into the lubricating oil. Therefore, the jacket water is heating very much more rapidly than the lubricating oil upon starting a cold engine, because, in this present system, the principal jacket water cooling is governed by heat exchanger 2. In the preferred method of operating this system, as the jacket water temperature becomes elevated to the operating range, the flow of heated water being returned to the engine through the by-pass pipe 13 is throttled by the valve 11, which, as has been explained, is operated in response to

the means 10 in pipe 9, said means 10 being thermally influenced, for example, by the temperature of the water flowing in pipe 9, to actuate valve 11, to reduce the flow through the by-pass pipe 13, thereby increasing the flow through the cooler 2 and reducing the temperature of the water being returned to the engine through pipe 9.

By this means, sufficient jacket water is forced through the cooler 2 to maintain a constant predetermined temperature of the jacket water regardless of the temperature of the sea water circulating through the jacket water cooler, and regardless of variations in the power being generated by the engine. Indicating the thermal-responsive element 10, as positioned in pipe 9, is optional, as a similar effect, i. e., the control of valve 11 in response to changes in the temperature of the circulating jacket water, may be obtained by placing the element 10 in pipe 14 beyond the connection thereto of by-pass pipe 13, or in pipe 15 at a point preferably between the engine and the valve 16.

With a substantially constant temperature maintained in the jacket water leaving the engine through the operation of the temperature control valve 11, causing more or less heat to be released by the heated jacket water, it will be noted that at any given engine power, the temperature of the jacket water and lubricating oil circulated to and from the engine remains substantially constant, regardless of all changes in the temperature or quantity of the sea water circulated through jacket water cooler 2. This is apparent by reference to the drawing. At constant engine power, heat dissipated to and from the oil and jacket water in the engine and the heat exchangers or coolers is substantially constant. Therefore, with a constant engine jacket water discharge temperature, the temperature of the jacket water entering the engine is substantially constant, because the rise in temperature of the water flowing through the engine is constant. Thus, the temperature of the jacket water leaving the lubricating oil heat exchanger 3 is constant, and as the amount of heat dissipated to the jacket water from the lubricating oil in the lubricating oil heat exchanger is constant, the temperature rise of the jacket water and lubricating oil to and from the lubricating oil heat exchanger remains constant. Thus, regardless of changes in the temperature and quantity of the sea water, the oil and the jacket water temperatures to and from the engine are maintained substantially constant at any given engine power, which is a very desirable engine operating condition from the standpoint of engine service life and reliability.

By properly proportioning the size of the heat exchangers, and by suitably adjusting the automatic control means, it is possible to provide for cooling the lubricating oil flowing to the engine to a temperature as low, or even lower, than the temperature of the jacket water flowing to the engine. Also, the system renders possible a minimum temperature rise of the jacket water flowing through the engine, which is very desirable for certain types of engine installations.

Referring to Fig. 2, which illustrates a modification of the system above described, it will be noted that a by-pass pipe 30 connects with the return jacket water pipe 9, preferably above the thermal-responsive unit 10, the other end of said pipe 30 being connected with the jacket water delivery pipe 15, preferably near its inlet, to the heat exchanger 3. It will be noted that this

by-pass pipe 30 is adapted to deliver jacket water which has been cooled by the cooler 2 into the stream of heated jacket water leaving the engine 1 through pipe 15, to blend therewith and to thereby modify the heat of the jacket water leaving the engine, and to re-circulate the admixture back through the heat exchanger 3 and the cooler 2.

The flow of water through the by-pass 30 is preferably governed by the temperature of the lubricating oil being circulated through the engine, and for that purpose a suitable three-way control valve 31, operatively connected by suitable means 32 with the oil temperature responsive governing means 33, may be employed. Said means 33 are indicated as connected with pipe 20, and adapted to be influenced by the heat of the lubricating oil leaving the engine therethrough, but the same may be inserted in the lubricating oil return pipe 22, or otherwise situated to accomplish the desired purpose. The by-pass pipe 18, and the means responsive to the lubricating oil temperature for controlling the flow of jacket water therethrough, are not shown in Fig. 2. It is to be understood, however, that the same may be incorporated therein, and further, that parts and combinations of parts of the system shown in either or both drawings may be interchangeable, depending upon the results it is desired to accomplish.

It will be noted that the by-pass 30 affords an efficient means for increasing the temperature difference between the fluids flowing through the heat exchanger 3, making it possible to readily increase or decrease the heating of the lubricating oil in close response to the automatic, thermal governing means. The adjustable valve 31 may be of the proportioning type, and preferably adapted to permit only a portion of the jacket water leaving the cooler 2 to be by-passed, to insure a sufficient flow of cooled jacket water to the engine. Element 10 in the system, shown both in Figs. 1 and 2, may be positioned in the delivery pipe 15 if it is desired that the heated jacket water temperature control the by-pass valve 11.

From the foregoing, it will be apparent that a very efficient system is provided for controlling the temperature of both the cooling water and the lubricating oil of the engine, by means of which the service life of internal combustion engines is improved, and the necessity for maintenance and repair decreased. Also, the improved system insures the rapid heating of chilled lubricating oil upon starting a cold engine, and the rapid warming up of a cold engine upon starting. The temperature of the jacket water and lubricating oil is controlled entirely automatically. The lubricating oil heat exchanger is not subjected to the corrosive action of sea water. The improved system permits of simplified piping arrangement and the control of the temperatures of both the jacket water and lubricating oil by simple, automatic governing means. The system has the additional advantage of providing for relatively small temperature rise of jacket water circulated through the engine with minimum size of lubricating oil heat exchangers.

It will be understood that, whereas the above description of the present engine cooling system is particularly adaptable to marine engine installations, it is equally applicable to all other internal engine installations. For land installations, the term "sea water," as employed herein, may be more properly termed "cooling water" or a cooling fluid obtained from an external source, and for

aircraft installations the primary cooling medium may be air.

It will be understood, as previously stated, that the above description and accompanying drawing comprehend only the general and preferred embodiment of the invention, and that various changes in construction, proportion and arrangement of the parts may be made within the scope of the appended claims without sacrificing any of the advantages of the invention.

What I claim is:

1. A system for controlling the temperature of the cooling water and of the lubricating oil of an internal combustion engine, including an internal combustion engine, a first heat exchanger for governing the temperature of the engine lubricating oil, a second heat exchanger for cooling the engine jacket water, means for circulating lubricating oil from the engine through the first said heat exchanger, means for circulating jacket water from the engine simultaneously through both of said heat exchangers, and means for controlling the quantity of water circulated through the second said heat exchanger for controlling the temperature of the jacket water leaving the engine.

2. A system for controlling the temperature of the cooling water and that of the lubricating oil for an internal combustion engine, wherein a first heat exchanger through which lubricating oil from the engine is circulated cools the water flowing from the engine, and a second heat exchanger is adapted to further cool said water, the heat transferring capability of the first said heat exchanger being governed by the water flowing from the second exchanger, controlling the temperature of the said lubricating oil, characterized by the fact that there is combined with the first said heat exchanger means governing the quantity of heated water flowing from said engine cooling system through said second heat exchanger and being admixed with water from the first said heat exchanger for delivery to the engine in a heated condition in order to elevate the temperature of the lubricating oil.

3. The method of controlling the temperature of the cooling water and that of the lubricating oil of an internal combustion engine, which comprises subjecting the lubricating oil in a flowing stream in indirect heat exchange relationship to a flowing stream of cooling water, simultaneously subjecting said stream of water in indirect heat exchange relationship to a flowing stream of coolant fluid at a temperature below that of said cooling water, and returning the cooling water thus treated to the engine for recirculation.

4. The method of controlling the temperature of the jacket water and that of the lubricating oil of an internal combustion engine, which comprises subjecting the lubricating oil in a circulating stream and in indirect heat exchange relationship to a circulating stream of jacket water, whereby the temperature of the lubricating oil is raised, subsequently subjecting the circulating stream of jacket water in indirect heat exchange relationship to a circulating stream of cooling fluid, and then returning the jacket water to the engine.

5. The method of controlling the temperature of the jacket water and that of the lubricating oil of an internal combustion engine, which comprises subjecting a circulating stream of jacket water to lesser cooling and to greater cooling in two separate heat exchange zones, subjecting a circulating stream of lubricating oil in indirect

heat exchange relationship to the water circulating through the zone of lesser cooling, and returning to the engine jacket water from either or both said zones, depending upon whether the heat of the jacket water entering the engine is above or below a predetermined operating temperature.

6. A system for controlling the temperature of the cooling water and that of the lubricating oil of an internal combustion engine, which includes a heat exchanger through which the cooling water of the engine is adapted to be circulated, means for circulating therethrough lubricating oil from the engine and in indirect heat exchange relationship with the circulating cooling water, and means controlled by the temperature of the lubricating oil for by-passing cooling water around said heat exchanger.

7. A system for controlling the temperature of the jacket water and that of the lubricating oil of an internal combustion engine, which includes a first and a second heat exchanger, means for circulating jacket water from the engine through said heat exchangers and back to the engine, means for circulating lubricating oil from the engine through the first heat exchanger and back to the engine, and means governed by the heat of the water leaving the second heat exchanger for by-passing water leaving the first said heat exchanger around the second heat exchanger, and returning the same directly to the engine.

8. A system for controlling the temperature of the jacket water and of the lubricating oil of an internal combustion engine, which comprises a heat exchanger through which lubricating oil from the engine is circulated, a jacket water cooler, means for circulating water from the engine through the heat exchanger and cooler, and temperature controlled means governed by the heat of the lubricating oil for by-passing jacket water around the heat exchanger.

9. A system for controlling the temperature of the jacket water and that of the lubricating oil of an internal combustion engine, which includes a lubricating oil heater and a jacket water cooler, means for circulating jacket water from the engine through said heater and said cooler and for returning the same to the engine, means for circulating lubricating oil from the engine through said heater and back to the engine, and means governed by the heat of the lubricating oil being circulated controlling the temperature of the jacket water leaving the engine.

10. A system for controlling the temperature of the jacket water and that of the lubricating oil of an internal combustion engine, which comprises a heat exchanger through which lubricating oil from the engine is circulated, a jacket water cooler, means for circulating jacket water from the engine through the heat exchanger and cooler, and temperature controlled means governed by the heat of the lubricating oil for by-passing jacket water around the engine.

11. A system for controlling the temperature

of the jacket water and that of the lubricating oil of an internal combustion engine, which comprises a heat exchanger through which lubricating oil from the engine is circulated, a jacket water cooler, means for circulating jacket water from the engine through the heat exchanger and cooler, and means controlling the heat transferring capability of the heat exchanger including thermally-governed means for by-passing water from said cooler, around the engine, for recirculation through the heat exchanger.

12. The method of controlling the temperature of the jacket water and that of the lubricating oil of an internal combustion engine, which comprises subjecting the lubricating oil in a circulating stream and in indirect heat exchange relationship to a circulating stream of heated engine jacket water, subjecting the heated jacket water in a circulating stream and in indirect heat exchange relationship to a circulating stream of coolant fluid, whereby the jacket water is cooled, passing cooled jacket water through the engine and then back to said heat exchange relationship with the lubricating oil, and simultaneously by-passing cooled jacket water around the engine and into the stream of circulating jacket water leaving said engine.

13. A system for controlling the temperature of the jacket water and that of the lubricating oil of an internal combustion engine, a heat exchanger, a jacket water cooler, means for circulating jacket water from the engine through the heat exchanger and the cooler to the engine, means for circulating jacket water from the cooler back to and through the heat exchanger, and means for circulating lubricating oil from the engine through the heat exchanger.

14. A system for controlling the temperature of the jacket water and that of the lubricating oil of an internal combustion engine, a heat exchanger, a jacket water cooler, means for circulating jacket water from the engine through the heat exchanger and the cooler to the engine, means for circulating jacket water from the cooler back to and through the heat exchanger, means for circulating lubricating oil from the engine through the heat exchanger, and means for bypassing jacket water from the engine around the heat exchanger to the cooler.
